Attorney.

UNITED STATES PATENT OFFICE.

JOSHUA JOHNSON, OF BRISCOE RUN, WEST VIRGINIA.

PORTABLE FENCE.

SPECIFICATION forming part of Letters Patent No. 283,114, dated August 14, 1883.

Application filed October 27, 1882. (No model.)

To all whom it may concern.

Be it known that I, JOSHUA JOHNSON, a citizen of the United States, residing at Briscoe Run, in the county of Wood and State of 5 West Virginia, have invented certain new and useful Improvements in Portable Fences, of which the following is a specification, reference being had therein to the accompanying drawings.

10 My invention relates to portable fences; and it consists in the construction and arrangement of its several parts, as will be hereinafter fully set forth, and pointed out in the claim.

15 In the drawings, Figure 1 is a perspective view of one of the posts, and Fig. 2 is a perspective of a section of the fence.

20 A are section-posts having braces *a* pivoted upon each side of their upper ends, said braces being arranged to spread out from each side 20 of the post and to hold the same securely in a vertical position, as shown. Suitable slots are arranged in the posts to permit the passage of the rails B.

25 C is center or brace, having braces *c* pivoted upon each side of its upper end, for the purposes hereinbefore set forth. The upper end is wider than the body of the post. It has formed in it a slot, *d*, into which turns the lock-bar D. Along the length of the post and cor-

30 responding to the slots in the posts A are recesses *d'*, in which rest the rails. Pivoted to the edge of the post, upon the same side as recesses, is lock-bar D, the upper end of which is cut to fit the slot *d*, as shown.

35 When the lock-bar is turned parallel to the post, it is seen that it will close the recesses *d'* and hold securely the rails therein. When the bar is turned at right angles to the post, the recesses will be uncovered and the post can be lifted away from the rails. I provide, however, that all posts may be constructed similar 40 to the center post.

What I claim is—

45 In a fence, the post having its top wider than the body, and braces pivoted upon each side thereof, and having suitably-arranged slots for the reception of the rails, and a lock-bar pivoted to its edge upon the same side as the slots, whereby when the bar is turned parallel with the post the rails are held securely 50 within the recesses, as shown.

55 In testimony whereof I affix my signature in presence of two witnesses.

JOSHUA JOHNSON.

Witnesses:

GEORGE LOOMIS,
L. N. TAVENNER.
